A. F. ROTH

CENTRIFUGAL FAN.

Filed May 31, 1923

INVENTOR
Adolph F. Roth
BY
W. T. Preswell,
ATTORNEY

UNITED STATES PATENT OFFICE.

ADOLPH F. ROTH, OF NEWARK, NEW JERSEY.

CENTRIFUGAL FAN.

Application filed May 31, 1923. Serial No. 642,522.

To all whom it may concern:

Be it known that I, ADOLPH F. ROTH, a citizen of the United States, and a resident of Newark, in the county of Essex and State of New Jersey, have invented certain new and useful Improvements in a Centrifugal Fan, of which the following is a full, clear, and exact specification.

This invention relates more particularly to a class of devices adapted to be used for circulating air.

My invention has for its object primarily to provide a fan designed to be employed in factories, restaurants, halls, buildings and elsewhere for maintaining healthful atmospheric conditions by causing effectual exhaustion of the air when charged with excessive heat, smoke, gaseous or acid fumes and other impurities as well as adapted for circulating air for cooling purposes and for circulating radiated hot air for heating purposes. The fan may also be used as an air blower, and is adapted to be centrifugally driven by wind or any suitable power; such as an electric motor, the fan being of a form serving to prevent contact of the exhausted air with the motor to overcome tendency to prematurely damage the parts thereof.

The invention contemplates mainly the provision of a surface element or flat disk which serves as a baffle and protector, and this element has a central hub portion which may be mounted on the shaft of an electrically driven motor, or other power. Fixed on one face of the surface element surrounding its hub portion are spaced radially disposed sets of air-suction elements or blades, each set composed of a multiple of spaced members, and the members of each set of the blades are bent substantially similar to the curvature of a tube or cone, while the outermost parts of the edges of the ends of each set of the blades are tapered toward the centers lengthwise thereof as well as tapered toward the hub portion of the surface element. When the fan is driven the air currents caused by the blades will be back-stopped by the baffle surface element, and the air currents will tend to be received in the inner ends of the blades for discharge in helical currents through the outer ends of the blades. The tendency to static pressure of the air currents at the hub portion of the surface element will thereby be prevented and effectual atmospheric circulation

will be accomplished whether the fan is driven at a slow or fast speed.

A further object of the invention is to provide a centrifugal fan of a simple, efficient and durable construction which may be made in any appropriate size and shape.

With these and other objects in view the invention will be hereinafter more fully explained with reference to the accompanying drawing forming a part of this specification in which similar characters of reference indicate corresponding parts in all the views, and will then be pointed out in the claims at the end of the description.

In the drawing, Figure 1 is a front elevation of one form of centrifugal fan embodying my invention.

Fig. 2 is an enlarged fragmentary view showing a side elevation of the fan applied to an electric motor as well as showing the manner of its use for exhausting air.

Fig. 3 is an enlarged front elevation of an assembled set of the blades used in the fan.

Fig. 4 is an enlarged plan of the blank from which one of the blades is formed, and

Fig. 5 is an enlarged plan of the blank from which the second blade is formed.

The fan has a surface element or flat disk or plate 10 which may be of any appropriate shape and size, though the disk is preferably circular with a hub portion, as 11, in its central part, and in practice the hub portion of the surface element or disk 10 may be mounted on the shaft, as 12, of an electric motor, as 13, or other suitable power driving means whereby the disk will be centrifugally driven.

On the face of the disk 10 opposite the shaft 12 may be one or a number of sets of multiple or pairs of air-suction elements or blades, as 14. In the drawing is shown a form of the fan having four sets or pairs of the blades, all of which are of similar formations, and these blades are arranged equidistant apart surrounding the hub portion 11 of the disk as well as being disposed radially relative to the hub portion.

Each set of the blades 14 may be in pairs, as shown, to include an inner member 15 and an outer member 16 spaced from the inner member, and each member of each pair of blades is formed from a blank, as 17, which may be of pliable sheet metal. The blanks of the inner members 15 of the blades are smaller than the blanks of the outer

members of the blades. Each of the blanks is approximately triangular in shape having two right-angled straight edges, as 18, 19, while the inclined edge of each blank may 5 be outwardly curved, as at 20, and one of the corner portions of each blank may be cut away transversely, as at 21, in parallel relation to the straight edge 19 of the blank. Each blank of the members of each pair of 10 the blades is bent so that the part at the edge 21 overlaps the central portion of the straight edge 19 to provide each blade with curved surfaces corresponding to the curvature of the surfaces of a tube or split tube 15 so that the blades will be of forms for taking currents of air with minimum resistance. The walls of the members of each pair of the blades are thereby substantially cone-shaped or cylindrical, and by curling the blank of 20 each member of each pair of the blades with the edge 21 lapping upon the edge 19, portions of the edges of the open ends of each member are tapered as at 22, 23, toward the center of the length of the blade. Each 25 pair of the blades are assembled with the inner member 15 being inserted within the outer member 16, and the inner members of the blades being smaller than the outer members, the tapered parts of the members of 30 each blade are spaced apart, as shown.

The sets of blades are arranged on the disk 10 with the outer faces of the triangulated edge parts of the outer members of the blades lying upon the disk, and the sets of 35 blades are also arranged with the triangulated edges of the members of the blades being in spaced parallel relation in cruciform fashion surrounding the hub portion. The tapered parts of the members of the blades are thereby disposed outermost from the disk, and the axes of the cylindrical or conical blades are substantially tangential to the hub portion. The blades may be secured to the disk by riveting or otherwise fastening, 40 as at 24, the overlapping edge parts of the members of each blade to the disk, and the outer members 16 of the blades may be connected by means of a ring or band, as 25, having spaced parts riveted, as at 25^a, to 45 each of the outer members, in order to reinforce the blades against tendency to swerve from their normal positions when under the pressure of suctional air-currents during the operation of the fan.

50 The fan may be employed in any suitable manner in factories, restaurants, buildings, cars, boats and elsewhere for producing sanitary atmospheric conditions by exhausting the air when charged with excessive heat, 55 smoke, gaseous or acid fumes and other impurities as well as being adapted for cooling purposes and for circulating radiated hot air for heating purposes or the fan may be used as an air blower. In the drawing is 60 illustrated the employment of the fan for

exhausting purposes, and wherein the fan with the shaft 12 and motor 13 is mounted in spaced relation to the outlet end, as 26, of a tubular duct or hood, as 27, which may lead from the place or locality from which 70 air is to be exhausted. The fan is also arranged so that the blades 14 are in opposition to the outlet of the hood, and when the fan is driven by the operation of the motor 75 the air-currents from the hood will be successively drawn by the inner ends of the members of the blades for passage through the outer ends of the blades and the currents of air will be admitted in spiral currents from the hub portion of the disk for passage and discharge through all members of the blades. The tendency to static air pressure prevailing at the hub will thereby be prevented, and the disk 10 serving as a baffle for receiving the currents of air provides 80 unusual efficiency in the operation of the fan whether driven at low or fast speeds, the disk also serving as a protector for the motor against liability to damage by contact with 85 the exhausted currents of air.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope 90 thereof.

Having thus described my invention, I claim as new and desire to secure by Letters Patent:—

1. A centrifugal fan, comprising a baffle surface element with a hub portion, a plurality of sets of spaced interfitting air-suction elements fixed on one face of the surface element surrounding the hub portion and each air-suction element including spaced inner and outer members, and the members of each pair of said air-suction elements curved approximately similar to the curvature of a tube, and all of the air suction elements being disposed radially relative to the hub portion of the surface element whereby the axes of said members are substantially tangential to the hub portion, the outer parts of the edges of the ends of the members of each pair of the air-suction elements being tapered toward the centers 105 of the lengths of the members as well as tapered toward the hub portion of the surface elements, and means connecting the outer faces of the outer members of all of the air-suction elements.

2. A centrifugal fan, comprising a baffle surface element with a hub portion, and a plurality of sets of spaced interfitting air-suction elements on one face of the surface element surrounding the hub portion and 110

each air-suction element including spaced inner and outer members, the members of each pair of said air-suction elements having walls curved approximately similar to the curvature of a slitted tube and the edges of the slits being fastened to the surface element whereby all of the air-suction elements are disposed radially relative to the hub portion of the surface element with the axes of said members substantially tangential to the hub portion.

3. A centrifugal fan, comprising a baffle surface element with a hub portion, and a plurality of sets of spaced interfitting air-suction elements on one face of the surface element surrounding the hub portion and each air-suction element including spaced inner and outer members, the members of each pair of said air-suction elements having walls curved approximately similar to the curvature of a slitted tube and the edges of the slits being fastened to the surface element whereby all of the air-suction elements are disposed radially relative to the hub portion of the surface element with the axes of said members substantially tangential to the hub portion, the outer parts of the edges of the ends of the members of each pair of the air-suction elements being tapered toward the centers of the lengths of the members as well as tapered toward the hub portion of the surface element.

4. A centrifugal fan, comprising a disk with a hub portion, and a plurality of spaced pairs of blades fixed on one face of the disk surrounding the hub portion and each blade including spaced inner and outer members, the members of each pair of said blades curved approximately similar to the curvature of a slitted tube and the edges of the slits being fastened to the surface element by a common means, and all of the blades being disposed radially relative to the hub portion of the disk whereby the axes of said blades are substantially tangential to the hub portion.

5. A centrifugal fan, comprising a disk with a hub portion, a plurality of spaced pairs of blades fixed on one face of the disk surrounding the hub portion each blade including spaced inner and outer members, the members of each pair of said blades curved approximately similar to the curvature of a tube, and all of the blades being disposed

radially relative to the hub portion of the disk whereby the axes of said blades are substantially tangential to the hub portion, the outer parts of the edges of the ends of the members of each pair of blades being tapered toward the centers of the lengths of the blades as well as tapered toward the hub portion of the disk.

6. A centrifugal fan, comprising a disk with a hub portion, and a plurality of spaced pairs of blades on one face of the disk surrounding the hub portion and each blade including spaced inner and outer members, the members of each pair of said blades having walls curved approximately similar to the curvature of a slitted tube and the edges of the slits being fastened to the disk whereby all of the blades are disposed radially relative to the hub portion of the disk with the axes of said members substantially tangential to the hub portion, and a band secured on the outer faces of all of the outer members of the blades.

7. A centrifugal fan, comprising a disk with a hub portion, a plurality of spaced pairs of blades on one face of the disk surrounding the hub portion, each blade including spaced inner and outer members and the members of each pair of said blades having walls curved approximately similar to the curvature of a slitted tube and the edges of the slits being fastened to the disk whereby all of the blades are disposed radially relative to the hub portion of the disk with the axes of said members substantially tangential to the hub portion, the outer parts of the edges of the ends of the members of each pair of the blades being tapered toward the centers of the lengths of the members as well as tapered toward the hub portion, and a band secured on the outer faces of all of the outer members of the blades.

8. A centrifugal fan comprising a disk, a ring spaced forwardly of the disk and a plurality of tubular blades interposed between the disk and ring, a second tubular blade within each of the first mentioned blades and connected therewith.

This specification signed and witnessed 105 this 29th day of May A. D. 1923.
